Gedersheim & Fairbanks.

ATTORNEYS.

UNITED STATES PATENT OFFICE.

MENDEL SCHWARTZ, OF BROOKLYN, NEW YORK.

POR-T-LIGHT.

1,361,551.

Specification of Letters Patent. Patented Dec. 7, 1920.

Application filed December 2, 1919, Serial No. 341,856. Renewed October 13, 1920. Serial No. 416,777.

To all whom it may concern:

Be it known that I, MENDEL SCHWARTZ, a citizen of the United States, residing formerly in the city and county of Philadelphia, State of Pennsylvania, now residing at Brooklyn, in the county of Kings, State of New York, have invented a new and useful Port-Light, of which the following is a specification.

10 My invention consists of a port light which is constructed of interfitting ring-like outer and inner members which are connectible by a movable joint which also permits the disconnection of said members, a 15 ring-like frame carrying reticulated material which is received in the outer ring-like member and is adapted to admit ventilation through the device and prevent the entrance of insects therethrough, means on the ring-like members for retaining said frame firmly 20 in position, and additional means on the outer member adapted to tighten the peripheral portion of said frame in the receiving ring.

25 The invention is satisfactorily illustrated in the accompanying drawing, but the important instrumentalities thereof may be varied, and so it is to be understood that the invention is not limited to the specific 30 devices shown and described, as long as they are within the spirit or scope of the claims.

Figure 1 represents a front elevation of a port light embodying my invention.

Fig. 2 represents a rear view thereof.

35 Fig. 3 represents a rear view of the exterior member of the device.

Fig. 4 represents a diametrical section of the reticulated member of the device.

Fig. 5 represents a diametrical section on 40 line 5—5 Fig. 2.

Fig. 6 represents a diametrical section on line 6—6 Fig. 2, including certain portions of the place of application of the device.

Fig. 7 represents a diametrical section of 45 portions of the members of the device in separated condition. Figs. 8 and 9 represent other embodiments of the invention.

Similar numerals of reference indicate corresponding parts in the figures.

50 Referring to the drawings.

1 designates the exterior member of the device, the same consisting of a ring having on its front portion the outturned bead 2, and the inturned rim or flange 3.

55 4 designates a ring-like frame to which the peripheral portion of the piece 5 of

gauze or other reticulated material is secured, said frame being seated against the flange 3 and so prevented from being displaced outwardly.

60 In order to hold said frame 4 in position on the flange 3 there are secured to the inner face of the ring member 1 the inturned lugs 6 whose outer ends are adapted to contact with the outer periphery of the frame 4 at intervals and grip tightly against the same whereby said frame 4 is prevented from rotation.

7 designates the inner member of the device, the same consisting of a ring having 70 on its front portion the outturned flange 8, and on its rear portion the inturned flange 9, the diameter of said member 7 being slightly less than the diameter of the member 1, it being noticed said member 7 is 75 adapted to enter the member 1 concentric therewith. Then the flange 8 bears against the frame 4 of the reticulated material and holds the same against inward motion and displacement, while the flange 9 contacts 80 with and overlaps the inner edge of the member 1 and forms a close joint therewith and correctly positions the member 7 for subsequent locking of the two members as will now be described.

85 On the inner face of the member 1 are the inturned studs 10 at intervals. In the member 7 are the L-shaped slots 11 at intervals adapted to receive said studs forming bayonet-joints for connecting the two members, 90 it being evident that when the studs enter the receiving portions of said slots, the member 7 is turned when said studs ride into the other portions of said slots and so the members are locked as most plainly 95 shown in Fig. 5, a feature not new *per se*.

When, however, the member 7 is turned in reverse direction, the studs are in communication with the receiving portions of the slots 11, then said member 7 may be drawn 100 out of the member 1 and entirely removed therefrom when so required.

105 On the inner side of the member 7 are the thumb or finger pieces 12 for convenience of turning or rotating the member 7.

In Fig. 6 is shown the collar 13 on the side of a ship or other place of service of the port light, the same being connected with said side or place by the bolts 14, and nuts thereon or other suitable means, it being noticed that the device is adapted to be fitted in said collar from without, when 110

the bead 2 of the outer member 1, which is of greater diameter than said collar, is adapted to abut the outer edge of the latter and prevents inward motion and displacement of the device through said collar, while the outturned flange 8 of the member 7 is of such width as to abut and overlap the inner edge of said collar, see Fig. 6, and so prevents outward motion and displacement 10 of the device through said collar, and then as the members of the device are interlocked and the device is controlled in opposite directions on the collar 13, and so remaining reliably in its applied position.

15 In order to hold the device tightly in the collar 13 there are secured to the exterior of the side of the outer ring 1 the resilient tongues 15, see Figs. 5, 7, 8 and 9, which project outwardly from said side and are adapted to enter said collar 13 and engage 20 the inner face thereof, and press against the same, as most plainly shown in Fig. 9, while also being resilient in their nature, and providing cushions which take up any 25 strain or shocks on the port light.

Having thus described my invention what I claim as new and desire to secure by Letters Patent, is:—

1. In a port light, inner and outer ring 30 members, a reticulated material in the outer member, and means adapted to connect said members, the outer ring member having an inturned rim on which the peripheral frame of said reticulated material is adapted to 35 be seated, the inner ring member having in front an interned rim which is adapted to bear against said frame, and at the rear an outturned flange which is adapted to over-

lappingly engage the inner edge of the outer ring member.

2. In a port light, inner and outer ring members, a reticulated material in the outer member, and means adapted to connect said member, the outer ring member having an inturned rim on which the peripheral frame 45 of said reticulated material is adapted to be seated, the inner ring member having in front an inturned rim which is adapted to bear against said frame, and at the rear an outturned flange which is adapted to over- 50 lappingly engage the inner edge of the outer ring member, said outer ring member having also in front an outturned bead which is continuous with the inturned rim on said member.

3. In a port light, inner and outer ring members, the outer member having in front an inturned rim, a reticulated member having a peripheral frame adapted to be seated on said rim, and means for locking said members and retaining said reticulated member in position on its seat, said outer member having thereon at intervals inward projections adapted to contact with said frame.

4. In a port light composed of inner and outer ring members, a reticulated material in the outer ring, a frame carrying said material, means on the inner ring adapted to engage said frame and resilient cushions on 70 the outer side of the outer ring.

MENDEL SCHWARTZ.
